UNITED STATES PATENT OFFICE.

HARRY SUMNER BEST, OF GALVA, ILLINOIS, ASSIGNOR TO CHARLOTTE S. BEST, OF GALVA, ILLINOIS, EXECUTRIX OF THE ESTATE OF JOHN H. BEST, DECEASED; SAID CHARLOTTE S. BEST ASSIGNOR TO JOHN H. BEST & SONS, A FIRM COMPOSED OF CHARLOTTE S. BEST, DON J. BEST, LEON H. BEST, AND HARRY S. BEST, ALL OF GALVA, ILLINOIS.

DISPLAY RACK.

Application filed April 20, 1923. Serial No. 633,465.

My invention relates to a display rack, and more particularly to a display rack adapted to be employed in connection with chenilles, carpets, canvas and goods of a similar character.

The chief object of my invention is to provide an improved display rack in which goods of the character described may be stored in compact rolls, each of the rolls being readily accessible for the purpose of display so that any desired length of goods may be withdrawn from a roll and displayed, and then either cut off from the roll or returned to the roll.

Other objects of my invention are to provide an improved display rack for goods of the character described in which means are provided for preventing rotation of the roll carrying members in one direction, in the opposite direction, and in both directions; which comprises means for guiding the goods so that compact rolls of aligned layers of the goods may be obtained, and which comprises brake means for controlling the speed of rotation of the rolls so that the inertia of the rotating roll will not cause more goods to be unrolled than is desired.

Other objects of my invention will become apparent as the detail description progresses, reference being had to the accompanying drawings, wherein

Fig. 1 is a perspective view of an improved display rack embodying the novel features of my invention.

Fig. 2 is a fragmentary front elevation showing certain parts of my improved display rack.

Fig. 3 is a fragmentary end elevation of the parts shown in Fig. 2.

Fig. 4 is a section taken on line 4—4 of Fig. 2.

Fig. 5 is a perspective view of an anti-friction bearing which I employ in my improved display rack.

Figs. 6, 7, 8, 9 and 10 are perspective views of certain details of construction.

Fig. 11 is a section taken on line 11—11 of Fig. 1.

Fig. 12 is a section taken on line 12—12 of Fig. 2.

Fig. 13 is a perspective view of a modified form of my invention, and

Fig. 14 is a section taken on line 14—14 of Fig. 13.

Similar characters of reference designate similar parts throughout the several views.

Referring to Fig. 1, the reference characters 10 and 10^a designate two frame members or standards, which are employed to support and carry a plurality of tubes 11, upon which goods such as chenilles and broadloom carpets may be rolled in compact form. The standard 10 comprises a pair of inclined leg members 12 and a cross brace 13. Each of the leg members 12 is provided with a foot 14 so proportioned that the standard may remain in upright position without securing it to the floor by means of bolts or other fastening means. However, I provide a plurality of apertured bosses 15 in each of the feet 14, and if so desired, the feet may be secured to the floor by means of bolts passed through the bosses. The standard 10^a comprises leg members 12^a, a cross brace 13^a and feet 14^a of identical construction with the similarly designated parts of the standard 10.

Each of the tubes 11 has its ends rotatably journalled in anti-friction bearings 16 mounted upon the standards 10 and 10^a.

As shown in Figs. 1 and 5 each of the anti-friction bearings mounted upon the standard 10^a comprises a bearing bracket 16 rigidly secured to the standard 10^a by bolts 17.

A plurality of anti-friction rollers 18 rotatably journalled in the bearing bracket 16 are adapted to rotatably journal one end of the particular tube 11 associated with the particular bearing bracket 16.

To prevent accidental displacement of the tubes relative to the bearing brackets 16 each of the bearing brackets is provided with a yoke 19 detachably secured to the bearing bracket by means of machine screws 20.

The anti-friction bearings rotatably journaling the tubes 11 upon the standard 10 comprise a plurality of bearing blocks 21 rigidly secured to the standard 10 by bolts 22 (Figs.

1, 2, 3 and 4). Each bearing block 21 has a central bore 23 adapted to receive the outer race 24 of a combined thrust and radial

ball bearing 25, the inner race 26 of the ball bearing 25 having driving engagement with a stud shaft 27. The stud shaft 27 is rigidly secured to and in one end of one of the tubes 11 by means of a pair of collars 28 and pins 29, the axes of the stud shaft 27 and its associated tube 11 being coincident (Fig. 4). The outer end of each stud shaft 27 is squared as at 30 to fit the socket 31 of the crank lever 32, which may be applied to any one of the stud shafts 27 to rotate that stud shaft and its associated tube 11 to roll or unroll goods upon or from the tube.

15 A ratchet 33 is rigidly secured to each of the stud shafts 27 by means of a set screw 34, the ratchets 33 being disposed adjacent the outer faces of the bearing blocks 21. A pawl 35 is provided for each of the ratchets 33, each pawl 35 being slidably mounted in one of a plurality of lugs 36 formed integrally with the bearing blocks 21. Each pawl 35 is provided with a hand piece 37, a cylindrical portion 38, a shoulder 39, and a beveled surface 40. The cylindrical portions 38 of the pawls 35 are adapted to fit snugly in squared apertures 41 formed in the lugs 36, the shoulders 39 being adapted to rest upon the upper surfaces 42 of the lugs 36 or in slots 43, one of which is formed in each of the bearing blocks 21 (Figs. 2, 3, 6 and 7). A cotter pin 44 is provided for each of the pawls 35 to prevent withdrawal of the pawls from the lugs and subsequent loss thereof.

Referring now to Figs. 2 and 3, it will be noted that the pawl 35 has its shoulder 39 resting upon the right hand portion of the surface 42 (Fig. 2), and that it will 40 lock the tube 11 against rotation in a counter clockwise direction (Fig. 3) but will permit the tube 11 to be rotated in a clockwise direction (Fig. 3). It is also apparent that if the shoulder 39 of the pawl 35 be shifted 45 to rest upon the left hand portion (Fig. 2) of the surface 42, the pawl 35 will prevent rotation of the tube 11 in a clockwise direction (Fig. 3), but that the beveled surface 40 of the pawl will permit the tube 11 to be 50 rotated in a counter clockwise direction (Fig. 3). Also, if the shoulder 39 be shifted to rest upon the forwardly extending portion 55 of the surface 42, the beveled edge 40 of the pawl 35 will not be in a position to cooperate with the ratchet 33. The cylindrical portion 38 of the pawl will then lock the ratchet 33, stud shaft 27 and tube 11 against rotation in either direction. The pawl 35 may be removed from engagement 60 with the ratchet 33 by placing the shoulder 39 in the slot 43 which is formed in the bearing bracket 21. When the pawl 35 is so withdrawn from engagement with the ratchet 33, the tube 11 is free to rotate in either direction.

Means are provided for securing one end or edge of the carpets or like articles which are to be wound upon the tubes to the tubes. These means comprise a plurality of clamps 45 shaped to conform with the cylindrical 70 surface of the tubes 11 and secured thereto by machine screws 46. As shown in Fig. 11 the machine screws 46 of each clamp 45 may be loosened to permit one edge of an article such as a carpet to be inserted between the 75 clamp 45 and the cylindrical surface of the tube 11. The screw 46 may then be tightened until the clamp 45 securely holds the article in place. When one edge of a carpet or the like has been secured to a tube 11 by 80 means of the clamps 45, the tube 11 may be rotated through the medium of the crank lever 32 and the carpet wound compactly about the tube 11. The tube 11 may then be locked against rotation by means of its associated ratchet 33 and pawl 35.

To guide the carpet when it is wound upon one of the tubes 11, and so as to form a compact roll having aligned layers, each of the tubes 11 is provided with a pair of guard wheels 47, a guard wheel 47 being disposed adjacent each end of the tube 11. Each of the guard wheels 47 is adjustably and frictionally secured to its associated tube 11, the guard wheel being constructed of 90 two separable, identical halves, as shown in Figs. 1, 3 and 12. The separable halves of each guard wheel 47 are secured to each other by bolts 48 which pass through split spokes 49 of the guard wheel at points adjacent the split hub 50 of the guard wheel. Each split hub 50 of the guard wheels 47 comprises a plurality of contact points 51 which are adapted to frictionally engage the outer cylindrical surface of the associated 105 tube 11 when the two halves of the guard wheel are drawn together by means of the bolts 48. It is readily understood that any one of the guard wheels may be adjusted longitudinally of its tube 11 by relieving the 110 tension upon the bolts 48 and sliding the guard wheel to a new position. The guard wheel may then be clamped in its new position by means of the bolts 48.

In the device which I have shown in the drawings, I prefer to use the guard wheels 47 adjacent the standard 10 as means, together with brake shoes 53, for controlling the speed at which the tubes 11 rotate when the carpets or other goods are being withdrawn from the tubes 11. I have learned that the weight of the material which is being withdrawn from a roll of goods is sufficient to cause the roll and its associated tube 11 to spin. Therefore, I have provided the 120 brake shoes 53, having fabricated linings 54, which may be brought into frictional engagement with the guard wheels adjacent the standard 10. As shown in Fig. 1 the 125 brake shoes 53, which are associated with 130

those tubes 11 having ends journaled in bearings on the inclined leg members 12, and also with the uppermost tube 11, are arranged in pairs. The brake shoe 53 which 5 controls that tube 11 having one of its ends journaled in a bearing on the cross brace 13 is pivotally secured to a lever 55. The lever 55 is rigidly secured to a shaft 56 rotatably journaled in a bearing 57 secured to the 10 cross brace 13 by means of bolts 58. The shaft 56 is disposed parallel to the tubes 11 and has its outer end squared as at 59 to receive the socket 31 of the crank lever 32, which may be employed to operate the brake 15 means as well as to rotate the several tubes 11.

Of the brake shoes 53 which are arranged in pairs, each brake shoe of a pair is pivotally secured to a lever 60 by one of a plurality of pins 61 (Fig. 3). Each of the levers 20 60 is rigidly secured to the inner end of a shaft 62 rotatably journaled in a bearing 63, each bearing 63 being secured to one of the inclined legs 12 by bolts 64-64. The 25 outer end of each of the shafts 62 is squared to receive the socket 31 of the crank lever 32, and by means of the crank lever either one of each pair of brake shoes 53 may be brought into frictional engagement with its 30 associated guard wheel 47.

While I have shown the brake shoes engaging certain of the guard wheels 47, it is apparent that if it were desirable to move these guard wheels toward the center of the 35 tubes for guiding goods upon the tubes, additional guard wheels of identical construction could be placed upon the tubes in alignment with the brake shoes to permit operation thereof.

40 In the operation of the device, one edge of a carpet or the like is secured to one of the tubes 11 by means of the clamps 45 in the manner aforesaid. By use of the crank lever 32 the operator may then rotate the tube 11 until the carpet is wound upon the tube in a compact roll, the guard wheels 47 serving to keep the side edges of the carpet in alignment with the roll. When the carpet or the like is to be displayed or removed from the tube 11, the crank lever 32 is associated with the particular brake shoe 53 controlling the tube 11 upon which the carpet or the like is wound. Then as the carpet is being withdrawn from the tube 11, the operator may check the speed of rotation of the tube 11 by varying the pressure with which the brake shoe 53 engages one of the guard wheels 47 carried by the tube.

55 The carpet may be rewound upon the tube by placing the crank lever 32 upon the squared end 30 of the stud shaft 27 carried by the tube 11, the operator simply rotating the tube 11 in a proper direction. Of course the pawl 35 may be employed to lock the 60 tube 11 against rotation in both directions

when the display rack or that particular tube 11 is not in use, and to lock the tube against rotation in one or another direction when a certain length of goods has been withdrawn from the roll and it is desired 70 to prevent further rotation of the tube.

In Figs. 13 and 14 I have shown a modified form of bearing which may be employed to rotatably journal the carpet carrying tubes. As shown, a tube 11^a having a clamp 45^a adjustably secured to the tube by a machine screw 46^a has one end rotatably journaled in a bearing 21^a. The bearing 21^a is rigidly secured to a standard 10^b by bolts 22^a. Rigidly secured to the outer end of the tube 11^a, which projects beyond the bearing 21^a, is a ratchet 33^a adapted to cooperate with a pawl 35^a pivotally secured to the bearing 21^a by a pin 35^b. The free end of the pawl 35^a is bifurcated to provide two teeth 35^c and 35^d. When the pawl 35^a is in the position shown in full lines in Fig. 14 the tooth 35^d is adapted to engage the ratchet 33^a, and to prevent rotation of the tube 11^a in a counter clockwise direction (Fig. 14), but to permit rotation of the tube 11^a in a clockwise direction (Fig. 14). If the pawl 35^a is shifted to occupy the position shown by dotted lines in Fig. 14 the tooth 35^c will engage the ratchet 33^a and prevent rotation 85 of the tube 11^a in a clockwise direction (Fig. 14) and permit rotation of the tube 11^a in a counter clockwise direction (Fig. 14).

90 A collar 11^b is rigidly secured upon the tube 11^a by a set screw 11^c, the collar being disposed adjacent the inner face of the bearing 21^a. The collar 11^b and the ratchet 33^a cooperate to hold the tube 11^a against longitudinal displacement relative to the bearing 21^a.

105 A longitudinal groove 21^b is formed in the inner cylindrical bearing surface of the bearing 21^a. Disposed in the groove 21^b and slidably journaled therein is a brake shoe 53^a having a fabricated lining 54^a adapted to frictionally engage the outer cylindrical surface of the tube 11^a. The force with which the brake shoe 53^a and its lining 54^a engage the tube 11^a may be regulated by means of a pin 53^b threaded into the bearing 21^a and adapted to engage the brake shoe 53^a. A handle 53^c is secured upon the outer end of the threaded pin 53^b so that the operator may adjust the pressure with which the brake lining 54^a engages the tube 11^a. It 110 will be readily understood that the brake shoe 53^a may be adjusted to lock the tube 11^a against rotation in either direction.

115 I am aware that changes in the form, construction and arrangement of parts may be made without departing from the spirit and without sacrificing the advantages of the invention and I reserve the right to make all such changes as fairly fall within the scope 120 of the following claims.

I claim:

1. In a device for displaying carpets and goods of a like character comprising a frame, a revolute member thereon and upon which the goods may be wound, a ratchet associated with said member, the combination with such ratchet member, of selective means comprising a single shouldered pawl with tapered end and a cooperating member with rectangular aperture, shoulder and slot for locking the revolute member against rotation in one direction only, the opposite direction only or in both directions, and means formed independent of said member for clamping one end of the goods to such member.
2. In a display rack of the class described wherein the goods are displayed upon a revolute member upon which they are wound, the combination with such revolute member, of means cooperable with such member for selectively locking the said member against rotation in one direction only, the opposite direction only, or in both directions.
3. In a display rack of the class described wherein the goods are displayed upon a revolute member upon which they are wound and from which they are unwound, the combination with such revolute member, of endwise and revolvably mounted means cooperable with said revolute member for selectively locking the same against rotation in one direction only, the opposite direction only, or in both directions.
4. In a display rack of the class described wherein the goods are displayed upon a revolute member upon which they are wound, the combination with such revolute member, of means embodying a toothed member on the shaft of the revolute member, and a shouldered pawl and a bearing block having a lug and a shoulder cooperable with said pawl for selectively locking the said revolute member against rotation in one direction only, in the opposite direction only, or in both directions.
5. In a display rack for displaying rugs and the like, wherein the rugs are wound upon a spindle, a stop comprising a toothed member on said spindle, a shouldered pawl with tapered end, and a cooperating member with rectangular aperture, shoulder and slot for selective engagement of the pawl therewith whereby said spindle may be locked against rotation in one direction only, in the opposite direction only, or in both directions.
6. In a display rack for displaying rugs and the like, wherein the goods are displayed upon a spindle upon which they are wound and unwound, a stop comprising a toothed member on the spindle, a shouldered pawl with tapered end, and a cooperating member with rectangular aperture, shoulder and slot, said pawl being rotatable and endwise movable in said last named member for selective engagement with the said aperture or shoulder or slot.

HARRY SUMNER BEST.
